UNITED STATES PATENT OFFICE

99,180

DESIGN FOR A DISPLAY DEVICE

Charles W. Ball, North Attleboro, Mass., assignor
to Marathon Company, a corporation of Mas-
sachusetts

Application January 17, 1936, Serial No. 60,643

Term of patent 3½ years

To all whom it may concern:

Be it known that I, Charles W. Ball, a citizen
of the United States of America, residing in North
Attleboro, county of Bristol, State of Massachu-
setts, have invented a new, original, and orna-
mental Design for a Display Device, of which the
following is a specification, reference being had
to the accompanying drawing, forming a part
thereof.

Fig. 1 is a front elevational view of a display
device, showing my new design; and Fig. 2 is a
side elevational view of the same. The shading
shows a contrasting appearance between the
background and mounting thereon.

I claim:

The ornamental design for a display device,
substantially as shown and described.

CHARLES W. BALL.
